UNITED STATES PATENT OFFICE.

THOMAS SLAIGHT, OF NEWARK, NEW JERSEY.

IMPROVEMENT IN MASTER-KEY LOCKS.

Specification forming part of Letters Patent No. **157,643**, dated December 8, 1874; application filed July 14, 1874.

To all whom it may concern:

Be it known that I, THOMAS SLAIGHT, of the city of Newark, in the county of Essex and State of New Jersey, have invented certain new and useful Improvements in Locks, of which the following is a specification:

This invention relates to the adaptation of that class of locks commonly called cylinder-locks to the reception of "master-keys," whereby any number of such locks, each one having a different subordinate key, can be opened by one master-key; and consists in so slotting the sliding plates of each lock actuated by a different subordinate key as to specially adapt it to be opened by a master-key common to any number of similar locks.

In the accompanying drawing is illustrated a cylinder-lock combining my improvements, in which the cylinder B is provided with a slotted post, E, which contains a number of sliding plates, *b*, of varying lengths and thicknesses, which operate in conjunction with other sliding plates, *c*, contained in a suitable box or case, F, inside of the lock-case, and in juxtaposition with the slotted post E, so that the ends of the sliding plates *b* and *c*, abutting against each other, must each present a smooth and even surface, in order that the post E may be made to rotate when the key is inserted to unlock the lock.

It will be obvious that an indefinite number of locks may be made, each requiring a separate key to unlock it, by simply changing the relative position of the sliding plates *b* and *c*, or in varying their lengths or thicknesses, or both, as a key must be fitted and adapted to each and every change.

The master-key is constructed to fit into the same key-hole as the subordinate key, and

into transverse slots *d* cut into the sliding plates *b*, common to and uniform in all the locks designed to be operated by such master-key, substantially as shown, so that the sliding plates are forced into the same relative positions in unlocking by the one key as by the other.

It is obvious that a master-key may in this manner be adapted as well to cylinder-locks having sliding pins as to those having sliding plates.

I do not claim the sliding bolt or latching mechanism connected thereto shown in the drawing, as those features already form the subject of a patent granted to me on the 6th day of November, 1860, and extended on the 6th day of November, 1874; they are only here introduced to show the adaptation of the invention herein claimed to such locks. Nor do I claim the special devices shown constituting this lock a cylinder-lock, such devices being likewise shown to illustrate the adaptation of my invention to a complete working lock; but, as my invention,

I claim—

A cylinder-lock having sliding plates *b*, provided with slots *d*, whereby any number of said locks, while each one may have a different subordinate key, are adapted to be opened by one and the same master-key, in the manner substantially as described and set forth.

In testimony that I claim the foregoing as my own invention I affix hereto my signature in presence of two witnesses.

THOS. SLAIGHT.
